US00D880412S

(12) **United States Design Patent** (10) Patent No.: **US D880,412 S**
(45) Date of Patent: ** Apr. 7, 2020

(54) **TIRE**

(71) Applicant: **Bridgestone Americas Tire Operations, LLC**, Nashville, TN (US)
(72) Inventors: **David E. Schultz**, Stow, OH (US);
Tanya L. Miracle, Uniontown, OH (US)

(73) Assignee: **Bridgestone Americas Tire Operations, LLC**, Nashville, TN (US)

(**) Term: **15 Years**

(21) Appl. No.: **29/660,684**

(22) Filed: **Aug. 22, 2018**

(51) LOC (12) Cl. **12-15**

(52) U.S. Cl. USPC **D12/604**; D12/594

(57) **CLAIM**

The ornamental design for a tire, as shown and described.

DESCRIPTION

FIG. 1 is a side perspective view of a tire showing our new design;

FIG. 2 is a front elevational view thereof;

FIG. 3 is a side elevational view of the left side thereof;
FIG. 4 is a side elevational view of the right side thereof;
and,

FIG. 5 is an enlarged fragmentary view thereof.

In the drawings, the broken lines depict environmental subject matter only and form no part of the claimed design.

1 Claim, 5 Drawing Sheets

FIG. 5
